UNITED STATES PATENT OFFICE.

LEWIS E. CURTIS AND JOHN MANOFSKY, OF WARREN, OHIO, ASSIGNORS TO YOUNGSTOWN PRESSED STEEL COMPANY, OF WARREN, OHIO, A CORPORATION OF OHIO.

EXPANDED-METAL MACHINE.

Original application filed December 8, 1922, Serial No. 605,734. Patent No. 1,493,956, dated May 13, 1924.
Divided and this application filed December 13, 1923. Serial No. 680,456.

To all whom it may concern:

Be it known that we, LEWIS E. CURTIS and JOHN MANOFSKY, citizens of the United States, residing at Warren, in the county of 5 Trumbull and State of Ohio, have invented a new and useful Improvement in Expanded-Metal Machines, of which the following is a specification.

The present invention relates to improvements in expanded metal machines and will be fully understood from the following description and the accompanying drawings in which:

Figure 1 is a partial side elevation of 15 one of the arms of the expanded metal machine;

Fig. 2 is a transverse section on the line 2 of Fig. 1;

Fig. 3 is a plan view of the bed of the 20 arm shown in Fig. 1; and

Fig. 4 is a partial enlarged longitudinal section through the expanding arm.

The expanded metal machine illustrated in the drawing is of the type of the machines 25 shown in prior patents to Lewis E. Curtis, Nos. 796,402 dated August 1, 1905, and 1,207,716, dated December 12, 1916, and is a division of application Ser. No. 605,734, filed Dec. 8, 1922, patented May 13, 1924,

1,493,956. In this type of machine a previously slotted blank is advanced longitudinally to two expanding arms which diverge vertically and transversely from the line of travel of the sheet, the blank being expanded 30 from its center outwardly by deflection of the strands of the blank and the unexpanded edge portions being held by the divergent expanding arms as they pass therethrough.

The blank which has been previously slotted is fed endwise to the guides 10 of the expanding arm 11 by means not shown herein. A similar expanding arm (not shown) turns down and the advancing slotted blank held 35 along its outer edges is expanded by the diverging arms. These oppositely disposed arms are substantially similar in construction and operation.

The upper expanding arm 11 is pivotally mounted at 12 on suitable brackets 13 on the main frame of the machine. At the outer end it is adjustably carried by a screw (not shown) so as to be movable up and down. 40

The expanding arm 11 is formed of a member 14 of somewhat U-shaped cross-section, in which are journaled shafts 15 to which are secured the grooved feed rolls 16, which are driven by a means (not shown) to advance the slotted blank outwardly along the expanding arm. These rolls are preferably formed of laminated construction, being made of circular plates 17 and 18 of alternately larger and smaller diameter. A grooved roll is thus formed, the grooves of which correspond to the width of depressions in the slotted blank resulting from the slitting operation.

The bed or way of the arms is made up by inserting spacers between the feed rolls 16. These spacers 19 and 20 are alternately 45 higher and lower, the higher being on substantially the same level as the tops of the rollers 16 and in alignment with the plates on these rollers, so that the grooves formed in the bed are continuous with and correspond to the grooves in the feed roll. It will be further noted that the lower spacers 20 are substantially of T-shape, the arms of the T extending into the grooves in the adjacent feed rolls and thereby serve also as 50 strippers for the feed rolls.

The spacers 19 and 20 are secured to the U-shaped member 14 by means of bolts 21. These bolts also pass through the trapezoidal plates 22, and through the serrated edge bar 23, the latter being continuous.

The spacers 19 and 20 between the feed rolls 16 have depending feet which rest upon a bar 24 which is secured to the U-shaped member 14 in any desired manner. 55 Screws 25 serve to hold the lower ends of the T-shaped spacers in position.

Above each feed roll 16 is mounted an upper feed roll 26 which is journaled on a shaft 27, the latter being carried eccentrically by a sleeve 28 which is journaled in suitable bearings on the expander-arm. At the end of each shaft 27 is mounted a gear 29 which meshes with a gear (not shown) on each shaft 15 so that these feed rolls constantly revolve together. The sleeve 28 is provided near the gear 29 with a projecting ear 30 into which is hooked the bent end of a rod 31 which passes through an opening in a lug 32 projecting from the framework 105 33. A wing nut 34 is screwed on the rod 31

and a coiled spring 35 extends from the projecting ear 32 to the winged nut 34. By screwing down or unscrewing the wing nut 34, the pressure may be adjusted on the 5 sleeve 28 and on the feed roll 26.

Between the upper feed rolls 26 are provided the spring pressed plungers 36. These are suspended by the bolts 37 which pass through the sleeve 38 mounted in a ledge 39 10 projecting from the upper frame 33. The nuts 40 on the bolts 37 determine the lowermost position of the plungers or feet 36. A coil spring 41 extends from each plunger into an opening in the ledge 39, the tension 15 of the spring being adjusted by means of the screw 42.

While we have shown and described certain embodiments of our invention, it is to be understood that it is capable of many 20 modifications. Changes therefore in the construction and arrangement may be made without departing from the spirit and scope of the invention as disclosed in the appended claims, in which it is our intention to claim 25 all novelty inherent in our invention as broadly as possible in view of the prior art.

We claim:

1. In a metal expanding machine, an expander-arm having a series of lower feed 30 rolls and spacer members between said feed rolls, said spacer members being formed of rolls, said spacer members being formed of adjacently positioned plates, alternately

higher and lower in elevation, whereby a grooved bed is formed.

2. In a metal expanding machine, an expander-arm having a series of lower feed 35 rolls and spacer members between said feed rolls, said spacer members being formed of adjacently positioned plates, alternately higher and lower in elevation, said plates 40 being bolted to the expander arm whereby a grooved bed is formed.

3. In a metal expanding machine, an expander-arm having a series of lower feed 45 rolls and spacer members between said feed rolls, said spacer members being formed of adjacently positioned plates, alternately higher and lower in elevation, said rolls having annular grooves matching said lower 50 plates, said lower plates extending into said grooves, whereby a grooved bed is formed.

4. In a metal expanding machine, an expander-arm having a series of lower feed 55 rolls and spacer members between said feed rolls, said spacer members being formed of adjacently positioned plates, alternately higher and lower in elevation, said rolls having annular grooves matching said lower 60 plates, said lower plates being T-shaped, the ends of said T extending into said grooves, 65 whereby a grooved bed is formed.

LEWIS E. CURTIS.
JOHN MANOFSKY.
